DESIGN FOR A TEXTILE FABRIC

Edwin Raphaels, New York, N. Y.

Application March 2, 1937, Serial No. 67,938

Term of patent 3½ years

To all whom it may concern:

Be it known that I, Edwin Raphaels, a citizen of the United States of America, residing in city of New York, county of New York, and State of New York, have invented a new, original, and ornamental Design for a Textile Fabric, of which the following is a specification, reference being had to the accompanying drawing, forming part thereof.

The figure of the drawing is a plan view of a textile fabric showing my new design.

The design unit is contained between the dot and dash lines, which unit is repeated in regular succession, as indicated by the extensions beyond the unit boundaries.

I claim:

The ornamental design for a textile fabric substantially as shown and described.

EDWIN RAPHAELS.
